Primary Examiner—Kay H. Chin*Attorney, Agent, or Firm*—Richard B. O'Planick; Lisa B. Riedesel[57] **CLAIM**

The ornamental design for a lawn cart, as shown and described.

DESCRIPTION

FIG. 1 is a top right front perspective view of a lawn cart showing our new design. The broken lines are for illustrative purposes only and form no part of the claimed design;

FIG. 2 is a front elevational view thereof; the rear elevational view being a mirror image;

FIG. 3 is a top plan view thereof;

FIG. 4 is a left side elevational view thereof;

FIG. 5 is a right side elevational view thereof; and,

FIG. 6 is a bottom plan view thereof.
